UNITED STATES PATENT OFFICE

105,792

DESIGN FOR A TEXTILE FABRIC

Curt Erwin Forstmann, Montclair, N. J.

Application May 9, 1935, Serial No. 56,742

Term of patent 14 years

To all whom it may concern:

Be it known that I, Curt Erwin Forstmann, a citizen of the United States, residing at Montclair, in the county of Essex and State of New Jersey, have invented a new, original and ornamental Design for a Textile Fabric, of which the following is a specification, reference being had to the accompanying drawing, forming part thereof.

In the drawing, the sole figure of which is a plan view of a piece of the textile fabric embodying the design of the present invention, the cloth depicted is of a single color.

The design comprises a woven nap fabric having a repeated design unit consisting of a pair of wide parallel nap stripes flanked by a pair of narrow nap stripes of substantially half the width of the wide nap stripes, background stripes between the wide nap stripes and between them and the narrow nap stripes, substantially of the same width as the narrow nap stripes, there being a wide background stripe separating the design units, the nap stripes being transversely convex.

I claim:

The ornamental design for a textile fabric as described and shown.

CURT ERWIN FORSTMANN.
